ELECTRON TUBE FOR PRODUCING ULTRA
SHORT WAVES

Wilhelm Eberhard Kühle and Felix Herriger,
Berlin, Germany, assignors to Telefunken Ge-
sellschaft für Drahtlose Telegraphie m. b. H.,
Berlin, Germany, a corporation of Germany

Application July 22, 1933, Serial No. 681,704
In Germany July 22, 1932

1 Claim. (Cl. 250—27.5)

The invention is concerned with electron or thermionic tubes adapted to the generation of ultra short waves of less than 1 meter (so-called decimeter waves). It is known from the prior art that in tubes of the said sort which are operated in what is known as a Barkhausen-Kurz circuit scheme predicated upon a positive grid and a negative anode, the grid and the anode, upon two opposite ends or sides of the tube, may be provided with leads so that, at one end the direct current supply lead may be connected, and at the opposite end the antenna by the aid of parallel wires (Lecher wires).

The present invention is particularly concerned with the construction and mounting of such a tube, more especially with the mode of holding or supporting both grid and anode. In tubes of the kind here mentioned and known in the prior art, the supply leads of grid and anode consist of slender flexible wires so that for the supporting and anchoring of these electrodes, special means such as glass rods, metallic supporter wires and equivalents, for instance, were required. All of this, however, tends to complicate the construction and mounting and renders difficult more particularly the exact centering of the electrode system or assembly, while at the same time the losses occasioned within the tube are raised.

According to this invention, the lead-ins are in the form of rigid rodlets, for instance, made of tungsten or molybdenum, while grid and anode are directly secured thereto with the result that they are supported by the supply leads at two ends.

One embodiment of the said idea is illustrated in Figure 1. Figure 2 shows a cross-section of the electrode assembly of Figure 1.

Referring to the same, 1 denotes the glass vessel or bulb having at two opposite ends the re-entrant portions and presses 2 and 3 in which latter are sealed by fusion the anode supporter wires 4, 5, and the grid supporter wires 6, 7. The cylindrical anode 8 by the aid of a slender metal tubelet 9 which itself may constitute part of the anode sheet, is shifted upon the leads 4 and 5. The grid 10 in a similar manner is secured by the aid of two tubelets or sleeve members 11 and 12 upon its supply leads 6 and 7.

Another reentrant portion and press 13 contains the leads 14, 15 for the filament 16. The cathode wire or filament is directly welded onto one of the supply leads 14, whereas it is united with the other wire 15 by way of a leaf spring 17 rather than immediately. The leaf spring 17 is conductively bridged by means of a flexible litzen-wire (stranded wire) 18, otherwise it would be unduly heated by the heating (filament) current.

Figure 2 shows a cross-section of the electrode assembly from which the mounting of the tube can be clearly understood. The anode and the grid, at the side facing towards the cathode press, have each a slot 19 and 20, respectively. These slots which are radially arranged with respect to the grid and anode axes make it possible to slip the cathode through said slots and into the grid-anode system after the latter electrodes have been mounted upon their supporter wires.

The sleeves marked 11 and 12 are rigidly connected with the grid by welding. Sleeve 12 is also rigidly connected with the grid supporting wire 7, while sleeve 11 is arranged so as to slide on wire 6 for reasons pertaining to assembling and the thermal expansion of the grid. The same holds true for sleeve 9 and wire 4. Leaf spring 17 serves for tensioning the cathode which expands when heated.

We claim:

An electron discharge tube comprising a cathode, grid and anode electrodes substantially surrounding the cathode, each of said grid and anode electrodes being provided at opposite ends with sleeve members, support rods extending in a direction parallel to the cathode connected to said sleeve members at corresponding ends of said electrodes and rigidly mounting said electrodes, and additional support rods also extending in a direction parallel to the cathode connected to the sleeve members at the opposite and corresponding ends of said electrodes and forming therewith a slideable connection for permitting expansion of said electrodes in a longitudinal direction but not in a transverse direction.

WILHELM EBERHARD KÜHLE.
